UNITED STATES PATENT OFFICE

VERNON C. GETZ, OF HAZLETON, PENNSYLVANIA

BROODER

Application filed May 29, 1931. Serial No. 541,002.

This invention relates to improvements in brooders.

The primary object of the invention resides in a compartment brooder which is equipped with specially constructed visors which will subject the chicks housed in the compartments to the health giving light rays, without subjecting them to the exciting influences of direct sunlight. This 10 feature serves to insure the health and speedy development of the chicks and cuts down chick mortality which is usually high in the common construction of brooder which subjects the chicks to the rays of brilliant sunlight.

Another object of the invention is to provide a chick brooder of the compartment type in which each compartment is heated in a manner to assure the chicks of a comfortable temperature ranging from room temperature at the front of the compartment to a higher temperature at the rear thereof. The difference of the heat temperature between the maximum and minimum 20 degrees is gradual so that a chick is free to choose a location which is most comfortable.

A further object of the invention is the provision of a chick brooder which may be 30 thoroughly cleaned when desired, by little effort which prevents the chicks from contracting such common diseases as roup, colds, brooder pneumonia, and the like, which diseases are usually communicated from one of a brood to another through droppings and other filthy litter. To overcome this unsanitary condition, I provide removable wire mesh floors in each compartment beneath which are arranged removable dropping pans whereby the droppings will pass through the wire mesh floor and be caught by the dropping pans.

A still further object is the provision of a chick brooder which affords perfect ventilation to allow a full sweep of air through the chick compartments. The amount of ventilation is regulated by the adjustment of the ultra-violet ray visor herein before mentioned to vary the amount of warm air 40 let out of the compartment and the amount

of cool air let in. This ventilation is especially important during the later stages of brooding and during hot summer periods when an abundance of air is required.

With these and other objects in view, the invention resides in the certain novel construction, combination and arrangement of parts, the essential features of which are hereinafter fully described, are particularly pointed out in the appended claims, and are 55 illustrated in the accompanying drawings, in which:

Figure 1 is a perspective view of a plurality of my compartment brooders arranged in deck or tier formation. 65

Figure 2 is a fragmentary perspective view of one of the anti-glare visors, and its adjustable support.

Figure 3 is an enlarged fragmentary plan view of a portion of the ray producing material from which the visors are constructed. 70

Figure 4 is a vertical sectional view on the line 4—4 of Figure 3.

Figure 5 is an end elevational view of several decks of brooders with the end walls 75 or grills broken away, and with parts shown in section.

Figure 6 is a detail perspective view of one of the chick trays or removable floors and certain of its correlated parts. 80

Figure 7 is a fragmentary detail vertical sectional view on the line 7—7 of Figure 5.

Figure 8 is a detail perspective view of one of the end walls or grill assemblies, 85 showing the parts in separated condition.

Referring to the drawings by reference characters, the numeral 10 designates my improved compartment brooder in its entirety, which includes a plurality of brooder sections 11 arranged in deck or tier formation, that is, one upon the other, and which brooder sections are supported upon an elevated base 12 from which rise vertical posts 13 to which the walls of the brooder compartments are connected. In view of the fact that each one of the brooder compartments is identical in construction, I will only describe the construction of one compartment which will suffice for the others. 90

Each brooder compartment 11 includes 100

grill side walls 14, each of which is provided with an upper feed grill portion 15 constructed of a plurality of spaced vertical bars and a lower baby chick feed grill portion 16 which is in the form of spaced circular openings. The numeral 17 designates end grill sections, each of which is provided with a central panel section 18 and an upper feed grill section 19 on opposite sides thereof beneath which are provided baby chick feed grill sections 20. The feed grill sections 19 are formed of a plurality of spaced vertical bars similar to the portion 15 of the side walls, while the lower baby chick feed sections 20 constitute spaced circular openings. The grill wall sections of one compartment are connected to the same walls of the next adjacent compartment by any suitable means but in the drawings I have illustrated dowell connections between these parts. By this construction, I produce a brooder of the knock-down or collapsible type to facilitate the compact shipping of the structure and the erection of the same by any one unskilled in the art.

Associated with the side and end grill sections are visors 21, each of which comprises a rectangular shaped frame 22 which supports a translucent panel 23. This panel 23 is provided with a screen 24 embedded in a glass body and which glass may be formed by spraying liquid glass upon the screen so that the same is received by the interstices of the screen. Also, the translucent panel may be made of "Cel-O-Glass", as set forth in U. S. Letters Patent No. 1,580,287. This glass from which the panel is formed may be of any desired color, such as blue, which will produce a subdued anti-glare ultra-violet ray when light is passed therethrough for a purpose to be presently explained. Although, I have described the visor as being constructed of glass, the same may be made of other translucent material, and also, the colors may be, red, amber, green, purple or the like if desired. Eyes 25 are carried by the top of the visor frame 22 adjacent the ends thereof and which engage hooks 26 mounted on the posts 13. By this hook and eye construction, the panels or visors are removably supported in position, and have pivotal movement in order that the angularity of the visors may be varied or adjusted to regulate the ventilation within the brooder compartments. For adjustably supporting the visors, I provide arms 27 which are pivoted to the post 13 by a thumb screw 28 and which screw when tightened is sufficient to support the arm 27 in an adjusted position. Extending inwardly from the free end of each arm is a pin 29 disposed in the path of movement of the visor and on which the ends of the visor frame rest.

Extending inwardly from the end panels 18 are cleats 30 which support a pair of

deflecting hovers 31, each hover constituting a semi-circular shaped member 32 and which pair are arranged centrally of the brooder compartment and extend lengthwise thereof. Housed within the hovers 31 are hot water heating pipes 33, which pipes are respectively connected to a hot water feed pipe 34 connected with a hot water furnace and with a return water pipe 35, which pipe is also connected with a hot water furnace to accommodate for the return flow of the hot water after passage through the heating pipes 33. The pipes 34 and 35 rise vertically at one end of the brooder and the lead-in branches are respectively connected to the pipes 33. Control valves 36 are provided with each branch pipe to regulate the heat of each compartment. It might be mentioned however that the hovers 31 are elevated with respect to the bottom of each compartment to permit chicks to pass therebeneath, or to hover thereunder.

Supported by each of the end grill sections 17 are spaced horizontally disposed cleats 37 and 38, the said cleats extending inwardly from opposite ends of the end grill sections as best seen in Figure 8 of the drawings. The cleats 37 slidably support foraminated tray sections 39 which are constructed of a frame 40 in which a wire screen 41 is mounted. The outer end of each tray 39 is provided with a feed pan seat 42 which extends beyond the side grill section when the tray section is in a fully inserted position for supporting feed trays 43, while the inner end of each tray frame is formed with a kerf 43 for receiving and supporting a vertical removable partition 44. The height of the partition 44 is such as to permit the said partition to pass under the hovers or heat deflectors 31 so that when the tray sections are in fully inserted position as shown in Figure 5 of the drawings, the said partition serves to divide each brooder unit into two separate compartments, each compartment being provided with three substantially open sides. However, should it be desired to throw the two separate compartments into a single compartment, the floor trays 40 may be removed and reinserted with the partitions 44 separated therefrom.

It will therefore be seen that the chicks may be segregated in each brooder section, or if desired, they may be given the free run of the entire section, merely by the use of the removable partition walls 44. By reference to Figure 5 of the drawings, it will be noted that one of the sliding tray sections is in a partially pulled out position so that the partition 44 is disposed adjacent the outer edge of one of the heat deflectors 31 to shut off or regulate the heat therefrom to the major portion of the compartment, or to prevent the chicks from hovering beneath the heat deflectors 31 when the temperature

of a room is sufficient for the comfort of the chicks.

Slidably supported upon the cleats 38 are dropping pans 45 which are insertible through opposite sides of the brooder compartment, and which pans are disposed directly beneath the foraminated floors or tray sections 39 for the purpose of catching the droppings of the chicks which pass through the openings in the screen 41. By this arrangement, the droppings are not collected upon the floor on which the chicks are supported, but filth is collected upon the dropping pans which may be removed when desired by merely sliding them from beneath the floor sections for cleaning purposes.

Brackets 46 extend outward from the end grill sections 17 and support water pans 47 which water is accessible to the chicks within the compartments by the extending of their heads through the bars of the grill sections 19, or through the openings in the lower chick feed grills 20.

From the foregoing description, it will be seen that I have provided a chick brooder which embodies a number of improvements in brooder construction, chiefly among which is the use of the ultra-violet ray producing visors which permits the ultra-violet rays of light to pass into the chick compartments with all their health giving properties, and which light rays produce a soft light which is conducive of the health and growth of the baby chicks. Although blue or violet color rays have proven more beneficial than others, various other colored rays may be produced such as red, amber, green, purple and the like. As stated, the visors may be adjusted as their angularity to regulate the admission of natural air into the brooder which dispenses with the usual practice of providing a humidifier for the ventilating air. Furthermore, all the parts are removable for permitting cleaning and disinfecting of the same which permits the maintenance of the brooder in a sanitary condition at all times.

The side grill sections 15 are each provided with a door for facilitating access to the interior of each compartment, but such door is only used for the purpose of inserting and removing the chicks from the compartments, as the trays and drop pans are all slidable through the sides of the brooder without reaching into the compartment.

While I have shown and described what I deem to be the most desirable embodiment of my invention, it will be understood that various changes in construction may be re-

sorted to if desired, and I do not limit myself to the precise structural details herein set forth, nor to anything less than the whole of my invention as set forth in the appended claims.

Having thus described the invention, what I claim as new and desire to secure by Letters Patent is:

1. A brooder comprising a grill body, a pair of heat deflectors mounted within said grill body, heating elements beneath said deflectors, a pair of floor sections slidably mounted in said grill body and movable through opposite sides thereof, and partition walls carried by the inner ends of said floor sections and movable beneath said heat deflectors for dividing the interior of said grill body into two separate compartments.

2. A brooder comprising a grill body, a pair of heat deflectors mounted within said grill body, heating elements beneath said deflectors, a pair of floor sections slidably mounted in said grill body and movable through opposite sides thereof, and partition walls carried by the inner ends of said floor sections and movable beneath said heat deflectors for dividing the interior of said grill body into two separate compartments, said partition walls being removably supported by said floor sections to enable the same to be removed therefrom to produce a single compartment within said grill body.

3. In a brooder, a grill body, a pair of semi-circular shaped deflectors mounted within said body side by side above the floor thereof, heating pipes disposed beneath said deflectors, and vertical partitions mounted for horizontal movement beneath said deflectors substantially as and for the purpose specified.

4. In a brooder, a grill body, a floor slidably mounted in said grill body through a side thereof, the outer end of said floor extending beyond the side of said body when fully inserted thereinto, a seat provided on the outer end of said floor, and a feed pan seated upon said seat.

5. In a brooder having a grill body, a heat deflector mounted within said grill body, a heating element beneath said deflector, a floor section slidably mounted in said grill body and movable through one side thereof, and an upstanding wall at the inner end of said floor section and movable beneath said heat deflector, substantially as and for the purpose specified.

VERNON C. GETZ.
